UNITED STATES PATENT OFFICE.

ISIDORE KRANZ, OF NEW YORK, N. Y.

DESIGN FOR A BRACKET ARM FOR LIGHTING FIXTURES.

Application filed February 20, 1926. Serial No. 16,612. Term of patent 7 years.

To all whom it may concern:

Be it known that ISIDORE KRANZ, a citizen of the United States, and resident of New York, in the county of New York and State of New York, has invented a new, original, and ornamental Design for a Bracket Arm for Lighting Fixtures, of which the following is a specification, reference being had to the accompanying drawing, forming part thereof, in which—

Fig. 1 is a side elevational view of a

bracket arm for lighting fixtures embodying my new design.

Fig. 2 is a front elevational view thereof.

I claim:

The ornamental design for a bracket arm for lighting fixtures as shown.

Dated at New York, county of New York, State of New York, this 17th day of February, 1926.

ISIDORE KRANZ.
